Inventor.
George H. Thomas
By *John H. Dillinger, Atty.*

UNITED STATES PATENT OFFICE.

GEORGE H. THOMAS, OF ERIE, PENNSYLVANIA.

METHOD OF MANUFACTURING FLEXIBLE COUPLINGS.

Application filed December 1, 1926. Serial No. 151,941.

This invention relates to the manufacture of flexible couplings for shafts, and particularly to such couplings known as of the jaw type, and consists in a method of manufacture whereby couplings are produced with little of any machine work, and method of lubricating same.

The features of my invention will hereafter be pointed out and explained and are 10 illustrated in the accompanying drawings in which:

Figure 1 is a side elevation of a jaw type of a shaft coupling.

Figure 2 is a like view showing the coupling separated.

Figure 3 is a section of a mold for molding coupling members, on a line drawn between the structural parts E and G.

Figure 4 is a vertical central section of 20 the same showing a coupling member in section therein.

Figure 5 is an end view of the complete mold.

Figure 6 is a transverse section of a flexible coupling showing method of lubricating the intermediate member of the coupling.

In these drawings A indicates the body members of a coupling, which are secured upon the ends of shafts B and B' desired 30 to be coupled. These body members are duplicates, and therefore, in this case require but one mold.

In carrying out my invention I prepare a mold consisting of two metallic portions 35 C and C' which are provided with ears c through which bolts c' pass, by means of which the portions C and C' of the mold can be securely clamped together, so that a mold cavity is formed within the walls of the mold of a conformation similar to the coupling body A shown in Figs. 1 and 2. A metallic core D, having an opening therethrough is placed in the central portion of the mold cavity, and a metallic cross-bar E 40 is inset in the edge of the open end of the mold portions C and C' which bar E serves as a core for the transverse slot between the shoulders a, a, on the coupling member A.

A bolt F extends centrally through the 50 mold portions C and C' and through the metallic core D, and through the cross-bar E. A cover plate G is placed on the bolt F, and a washer f and nut f' placed on the bolt F and the cover plate G securely

clamped in place, and the nuts c' on the 55 bolts c are screwed up tight so that all parts of the mold are securely clamped together. The mold portions C and C' are provided with duct portions H which fit together, when the mold portions are clamped together, and form a duct portion H, through which molten metal can be forced into the mold cavity, to cast a coupling member A.

In practicing my invention the mold shown in Figs. 3, 4 and 5 is prepared with 60 a mold cavity for casting shaft coupling members of the jaw type, as shown in Figs. 1 and 2, and I preferably use suitable metal such as Monel metal, or other metal suitable 65 for die casting, which in a molten state I 70 force into the mold cavity under pressure, so that all parts of the cavity are filled. By using a metallic die or mold the surface of the article will be smooth, and will not require any machine work to prepare it for 75 assembly.

In Figure 6, I show the square block, or intermediate member, of a shaft coupling which is adapted to fit between the shoulders a on the coupling member A. Adjacent to 80 the corners of this block a are placed holes in which I place blocks of graphite J which fit the openings loosely, so that as the coupling revolves said blocks of graphite will be forced outwardly by centrifugal force, 85 against the flat faces of the shoulders a, and thereby be maintained against the shoulders a whereby graphite is abraded from said graphite blocks as the two members A, A work past each other during the operation 90 of the coupling, and in this manner maintain the two members A, A and the edges of the intermediate block member A' sufficiently lubricated.

Having thus fully shown and described 95 my improved method of making coupling members of the jaw type so that others can utilize the same what I claim as new and desire to secure by Letters Patent is:

1. In a mold of the class described, a 100 pair of metallic mold sections, means to secure said mold sections together, a transverse metallic mold bar, a central core within in said mold, a plate to close said mold and means to clamp said plate in place.

2. In a metallic mold, a pair of mold sections including a channel for admission of molten metal, sectional cores within said

mold sections, means to secure said mold sections together, a plate to close said mold, and means to secure said plate in place.

3. In a metallic mold, a pair of mold sections including a channel for admission of molten metal, means to secure said mold sections together, a central metallic core, a

transverse core bar, a cover plate to close said mold, and a bolt through said mold, cores and cover plate whereby said cover 10 plate and cores are secured in place.

In testimony whereof I affix my signature.

GEORGE H. THOMAS.
